UNITED STATES PATENT OFFICE.

JOSEPH EDWARD BIGGS, OF CLAY CITY, INDIANA.

DESIGN FOR A FLOWER-POT.

SPECIFICATION forming part of Design No. 27,380, dated July 20, 1897.

Application filed May 25, 1897. Serial No. 638,162. Term of patent 7 years.

To all whom it may concern:

Be it known that I, JOSEPH EDWARD BIGGS, a citizen of the United States, residing at Clay City, in the county of Clay and State of Indiana, have invented and produced a certain new and original Design for Flower-Pots; and I do declare the following to be a full, clear, and exact description of the invention, such as will enable others skilled in the art to 5 make and use the same.

My invention has relation to a new and original design for a flower-pot; and it consists of a flower-pot of the configuration and ornamentation shown in the accompanying 15 drawing, in which I have illustrated my invention in perspective.

The leading features of my design consist of a body 1, having a flat base and gradually curved sides and top, which is formed with a deep recess, within which is adapted to be 20 placed soil and the growing plants.

The end of the pot may be suitably inscribed and the body may be ornamented with vines, as shown.

What I claim is—

The design for a flower-pot, as herein shown and described.

In testimony whereof I hereunto affix my signature in presence of two witnesses.

JOSEPH EDWARD BIGGS.
